AIR CONDITIONING SYSTEM UTILIZING
REFRIGERATIONRobert T. Palmer, Sharon, Mass., assignor to
B. F. Sturtevant Company, Boston, Mass.

Application September 8, 1939, Serial No. 293,939

1 Claim. (Cl. 62—6)

This invention relates to air conditioning systems utilizing refrigeration and relates more particularly to air conditioning systems utilizing refrigerant compressors, for railway passenger cars.

In the past, it has been the practice in air conditioned railway passenger cars, to supply 75% recirculated air and 25% outdoor air. Utilizing such large proportions of recirculated air reduces the refrigerating load but the conditioned air does not have the desired freshness and the odors are objectionable.

This invention provides for utilizing all outdoor air except at such times that the refrigeration plant will be overloaded or the expense of conditioning all outdoor air is out of proportion to the benefits.

An object of the invention is to increase the proportion of outdoor air supplied in air conditioning systems.

Another object of the invention is to control the supply of outdoor air in an air conditioning system by a thermostat which indicates the load upon the refrigerant compressor used.

Other objects of the invention will be apparent from the following description taken with the drawing.

The invention will now be described with reference to the drawing which illustrates diagrammatically one embodiment of the invention in a railway passenger car.

The blower 5 draws in outdoor air through the inlet 6, and recirculated air through the inlet 7, and forces the air through the air cooler 8 and then through the duct 9 into the passenger space.

The electric motor 10 drives the refrigerant compressor 11 which supplies refrigerant to the condenser 12 and then through the pipe 13 and expansion valve 14 through the direct expansion tubes 4 in the air cooler 8, the evaporated refrigerant returning through the pipe 15 to the suction side of the compressor.

The fresh air inlet 6 contains the dampers 16 and the recirculated air inlet 7 contains the dampers 17 which are adjusted by the electric motor 18 under the control of the duct thermostat 19.

The thermostat 20 in the passenger space controls the operation of the compressor 10. When the temperature in the passenger space rises above the control temperature, which may be 75° F., the contacts of the thermostat 20 close and complete the electric circuit including the wire 21, the electric source 23, the wire 24, the motor 10 and the wire 25.

This energizes the compressor 11, causing it to supply refrigerant to the air cooler 8 for chilling the air moved through the cooler and supplied into the passenger space.

The duct thermostat 19 is connected in the electric circuit including the wire 26, the electric source 23, the wire 27, the damper motor 18 and the wire 28.

The contacts of the duct thermostat 19 are adjusted to close for temperatures below say 65° F. When the air from the cooler is below 65° F., the contacts of the relay 19 close the last described circuit including the damper motor 18 causing it to adjust the dampers 17 to closed position and the dampers 16 to full open position. The cooler 8 then chills all outdoor air and no recirculated air is supplied into the passenger space.

If the condition of the outdoor air becomes such that the refrigeration equipment becomes overloaded or the load upon it becomes such that conditioning all outdoor air would not be practical, the evaporator tubes 4 will not be able to chill the air below the desired control temperature of 65° F., and the duct thermostat 19 will open its contacts to open the above described electric circuit including the damper motor 18, causing the motor 18 to adjust the dampers 16 and 17 to partial recirculation.

During the off cycles of the compressor, there will be no chilled air from the cooler 8 to actuate the thermostat 19 and the dampers will be adjusted for partial recirculation.

The temperature and pressure of the refrigerant vapor in the suction pipe 15 also reflect the condition of the evaporator tubes 4, that is, whether they are overloaded or not. The thermostat 29 may be connected to the suction pipe 15 to respond to the temperature or pressure therein or to both, and may be connected as shown by the dotted lines on the drawing or as an alternate control in substitution for the duct thermostat 19.

What is claimed is:

An air cooling system comprising refrigerant evaporator tubes arranged as air cooling tubes, means for supplying outdoor air and air recirculated from the space served, to said tubes for cooling, refrigerating means including a compressor for supplying refrigerant to said tubes, means including a thermostat in the space served for controlling said compressor, means forming an outlet for the air from said tubes, into said space, and means including a second thermostat exposed to the air from said tubes and located between said tubes and said outlet, for adjusting said first mentioned means to increase the proportion of outdoor air when the temperature of the air from said tubes is below a predetermined point and for increasing the proportion of recirculated air when the temperature of the air leaving said tubes is above said point.
